(57) **CLAIM**

The ornamental design for a glove, as shown and described.

DESCRIPTION

FIG. 1 is a front elevation view of the glove showing our new design;

FIG. 2 is a rear elevation view thereof;

FIG. 3 is a right side elevation view thereof;

FIG. 4 is a left side elevation view thereof; and,

FIG. 5 is a front perspective view thereof.

The broken lines showing the remainder of the glove illustrate environmental subject matter that forms no part of the claimed design.
